UNITED STATES PATENT OFFICE.

EDWARD P. HURD, OF BOSTON, MASSACHUSETTS, ASSIGNOR TO UNITED SHOE MACHINERY COMPANY, OF BOSTON, MASSACHUSETTS, A CORPORATION OF NEW JERSEY.

NAIL.

SPECIFICATION forming part of Letters Patent No. 767,520, dated August 16, 1904.

Application filed November 17, 1899. Serial No. 737,284. (No model.)

To all whom it may concern:

Be it known that I, EDWARD P. HURD, a citizen of the United States, residing at Boston, in the county of Suffolk and State of Massachusetts, have invented an Improvement in Nails, of which the following description, in connection with the accompanying drawings, is a specification, like characters on the drawings representing like parts.

10 This invention has for its object the production of a novel nail adapted to be driven into a heel to attach it to a sole, said nail presenting near one end an upper portion shaped to easily penetrate the inner side of a top lift spanked on the heel after the same has been 15 nailed to the sole, the upper portion of the nail presenting a large extent of holding-surface.

My novel nail consists of a shank or body 20 having a suitable clenching-point, a collar extending from said body, and an upper portion rising from said collar and adapted to penetrate a top lift, said upper portion being of a length preferably less than the thickness of 25 the top lift to be held by it and recessed or indented below its top end. The recesses or indentations, one or more, leave each a lip standing at or near the extremity of the upper portion farthest from the collar, into 30 which recesses the stock of the top lift partially penetrated by the upper portion and expanded may contract to thus retain the top lift impaled on the upper portion of the nail.

35 Figure 1, in cross-section, shows a heel connected with a sole and upper by a nail made in accordance with my invention, said nail holding the top lift in place. Fig. 2 is a much enlarged side elevation of my improved nail. 40 Fig. 3 is a top view thereof. Fig. 4 is another view of the nail shown in Fig. 2 looking at it from the right. Fig. 5 is a section on the line $x'x'$, Fig. 4.

My improved heel-nail consists, essentially, 45 of a body a , provided with a clenching-point b of any usual or suitable kind, the body and point constituting a shank, which is provided with a collar c , having rising from it an up-

per portion d . The under side of the collar at its junction with the body of the nail preferably presents a reinforcing-enlargement d' , which adds very materially to the strength of the nail and prevents the body from being broken transversely in line with the under side of the collar. A nail without such reinforcing-enlargement is liable to be broken when driven into a solid heel. The upper portion d rises centrally from the collar and has a curvilinear top end which preferably will be flat, said top end, as herein represented, being of substantially circular form or of substantially the same shape as the body of the main part of the shank of the nail, and below its top end the said upper portion is recessed and indented on one or more sides, as at e , to 55 leave thin-edged lips f , (see Figs. 2 and 4,) which are in the plane of the said curvilinear top end. The recess e is made of a length nearly or quite equal to the full length of the upper portion. When the upper portion is 60 recessed oppositely, any cross-section of the body of the upper portion, as on the line $x'x'$, Fig. 4, will show two longer parallel lines 2 3, (see Fig. 5,) which constitute the longer sides of the upper portion, said lines crossing the 65 central part of the collar at each side the axial center of the body of the shank, the two shorter ends 4 and 5 of the upper portion terminating, preferably, near the periphery of the collar. The recesses or indentations afford 70 spaces below the lips f , in which a part of the substance of the top lift spanked upon said portion may enter, thus enabling the top lift to be held in place on the upper portions of a plurality of driven nails.

I have shown the top of the upper portion as circular; but it may be elliptical or of any other outline in which the top edge is formed in a continuous curve.

By forming my nail, as shown, with an upper portion formed in a continuous curve at its top and recessed below the top I am able to secure in one nail facility of entrance into the stock combined with great holding power for the surfaces of the recessed portions. The 90 upper portion with a top of such shape enters

the stock more readily than it would if otherwise shaped, and the recesses formed by cutting away below the top of the upper portion afford a great extent of holding-surface. Re-
cessing the side of the upper portion at more
than one place affords additional holding
means for the top lift, and I prefer to form
the recesses on two opposite sides, as shown
in the drawings. When the recesses are
formed on two sides of the upper portion, the
above-mentioned advantages—that is, a com-
bination of great facility of entrance into the
stock and great holding power for the sur-
faces of the recessed portions—are best se-
cured by so forming the said recesses that the
distance between the opposite walls of the up-
per portion shall be least in substantially the
diameter of the nail, and by the expression
“least” I mean that the distance between said
walls in a diametrical line shall not exceed the
distance between said walls at any other part
thereof. It is also preferable that the lips
formed above said recesses shall be at the ex-
tremity of the upper portion.

25 The collar on the nail herein shown is re-
presented as circular, and the lines of the walls
of the upper portion at the deepest parts of
the recesses are made to constitute chords of a
circle described within the collar from the
30 longitudinal axis of the nail.

To illustrate my nail applied as it will be in
practice, I have in Fig. 1 shown a heel hav-
ing a top lift held in place by one of my novel
nails *a*. In that figure, *A* represents the body
35 of the heel, *B* the top lift, *C* the upper, *D* the
counter, and *E* the lining, of a shoe.

Having described my invention, what I
claim as new, and desire to secure by Letters
Patent, is—

40 1. As an improved article of manufacture,
a nail having a collar and an upper portion
above said collar, said upper portion having
a top edge formed in a continuous curve and
being cut away between its end and said col-

lar to form a recess, the deepest part of said 45
recess being on a line substantially parallel
with a diameter of the nail-body, said recess
forming with the top end an overhanging lip
situated in the plane of said end.

2. A nail having a shank, a collar, and an 50
upper portion above said collar, said upper
portion having its top edge formed in a con-
tinuous curve and having separated recesses
in opposite sides which form overhanging
55 lips situated in the top end, the said recesses
having their deepest portions along straight
lines and being of such a depth that the thick-
ness of the upper portion is nowhere less than
along the diameter of the nail in the plane of
and at right angles to said straight lines. 60

3. A heel-nail having a shank, a collar, and
an upper portion above said collar, said up-
per portion being recessed on opposite sides
65 to form overhanging lips situated in the top
end of the nail with a thin web or wall con-
necting the lips and the collar, said web being
substantially rectangular in section at its thin-
nest part and of a width greater than its thick-
ness, and the recesses in the upper portion
70 each being of a length equal to the major part
of the length of said upper portion.

4. A nail having a shank, a collar, and an
upper portion above said collar, said upper
portion having a flat end and being recessed
75 or indented on opposite sides to thereby form
overhanging lips extending from, and located
in the plane of the top of the upper portion,
and a thin web or wall connecting the lips
with the collar, said web being nowhere thin-
ner than on a diameter of said nail. 80

In testimony whereof I have signed my name
to this specification in the presence of two sub-
scribing witnesses.

EDWARD P. HURD.
